UNITED STATES PATENT OFFICE.

ALBERT N. THOMAS AND JOHN CALDWELL, OF AVALON, MISSOURI.

THRESHING-MACHINE.

SPECIFICATION forming part of Letters Patent No. 655,915, dated August 14, 1900.

Application filed October 31, 1899. Serial No. 735,405. (No model.)

To all whom it may concern:

Be it known that we, ALBERT N. THOMAS and JOHN CALDWELL, citizens of the United States, residing at Avalon, in the county of 5 Livingston and State of Missouri, have invented certain new and useful Improvements in Threshing-Machines, of which the following is a specification.

Our invention relates to threshing-machines, and particularly to grain-separators, and has for its object to prevent the choking or clogging of the sieve by particles of straw or weed falling perpendicularly on such sieve by causing such particles to fall horizontally 10 or at an angle on the sieve. This object we accomplish in the manner and by the means hereinafter more fully described in detail and particularly pointed out in the claim, reference being had to the accompanying 15 drawings, in which like letters indicate like parts in all the views.

Figure 1 is a perspective view of our invention. Fig. 2 is a like view of the perforated extension of a grain-pan with our invention 20 attached. Fig. 3 is a longitudinal vertical section.

Our invention consists of the inclined shelves A, secured at their ends to the side pieces B of a frame B', so that the upper edge 30 of one shelf will be immediately over the lower edge of the preceding shelf, leaving a vertical opening C between the upper edge of the one and the lower edge of the other, varying according to the pitch and width of the shelves 35 A. Said shelves A incline rearwardly and downwardly in the direction of the flow of the straw, weeds, or other material passing over the same and direct or deliver said straw to the sieve in a horizontal position, or at least 40 at an angle to the perpendicular. The rearward and downward inclination of the shelves A also serves to prevent the clogging of the

sieve G by giving an impulse rearwardly to the course of the material as it passes over the shelves and descends to said sieve. The 45 side pieces B are adapted to be secured to the sides of the perforated extension D of the grain-pan E, so that the shelves A will extend across under such perforated extension D and receive what falls from such extension D. 50

F is a shoe arranged to operate in usual manner, and G an inclined sieve in said shoe, which is adapted to receive the particles of straw and weeds from the inclined shelves of the frame B. 55

The operation of our invention is as follows: The grain, accompanied by the chaff and particles of straw and weeds, falls through the perforations of the extension D on the shelves A and passes down the inclined surfaces of 60 such shelves A to the openings C, through which the particles of straw and weed pass in a horizontal position, or at least at an angle to the perpendicular, thus lessening the chance of their sticking in the meshes of the sieve G 65 and choking or clogging it.

Having thus described our invention, what we claim as new, and desire to secure by Letters Patent, is—

In a threshing-machine, a grain-pan with 70 a perforated extension, a detachable frame adapted to be carried on the under side of said extension, and having a series of imperforate shelves inclined rearwardly and downwardly in the direction of flow of material 75 passing over the same, substantially as shown and described.

In testimony whereof we hereto affix our signatures in the presence of two witnesses.

ALBERT N. THOMAS.
JOHN CALDWELL.
